H. L. PAGE.

REPRODUCER FOR SOUND RECORDS.
ORIGINAL FILED SEPT. 12, 1921.

Inventor:

Howard L. Page,

By *Greene & Cox*

Attorneys

UNITED STATES PATENT OFFICE.

HOWARD L. PAGE, OF CHICAGO, ILLINOIS.

REPRODUCER FOR SOUND RECORDS.

Original application filed September 12, 1921, Serial No. 500,012. Divided and this application filed May 3, 1922. Serial No. 558,269.

To all whom it may concern:

Be it known that I, HOWARD L. PAGE, a citizen of the United States, residing at Chicago, in the county of Cook and State of Illinois, have invented a certain new and useful Improvement in Reproducers for Sound Records, of which the following is a specification.

This invention is a machine of the phonographic type for reproducing sound from a record of the type shown, described and claimed in my original application, Serial No. 500,012, filed September 12, 1921, of which this is a division.

The object of the invention is to produce a machine which will operate upon records made by said prior patent application and, as a result thereof, deliver into the ear audible sounds substantially identical with those originally entering the recording machine.

The invention consists in a machine capable of attaining the foregoing objects, which can be easily and cheaply made, which is satisfactory in use, and is not readily liable to get out of order.

The invention further consists in many features and details of construction which will be hereafter more fully set forth in the specification and claims.

Referring to the drawings, in which like numerals designate the same parts throughout the several views:

Figure 1 shows the reproducing machine by which a commercial sound record of the type produced by the machine of said prior application is used to reproduce the original sounds. This figure is a side view of the mechanism of Figure 2.

Figure 2 is a plan detail view of the mechanism of Figure 1.

Figure 3 is a detail of the pivot mechanism for the record reproducing bar taken from approximately the points indicated by the arrows at 3—3 of Figure 2.

Figure 4 is an enlarged detail view of the reproducing bar showing the manner in which it contacts the reproducing record in transmitting what is on it into audible sound.

Figure 5 shows an electric circuit and mechanism inserted therein by which the reproducing apparatus of this invention may be used to produce the actual sounds which are on the record at any distance from

the main machine, either a few feet or many miles.

For the purpose of insuring identity of this divisional application with the original application, said figures are merely reproductions of said Figures 23 to 27 of said original application with only the figure numbers changed, the letters of reference on the figures being otherwise those of the original application.

The mechanism of the original application forms a record, shown in Figures 2 and 5, comprising a flat tape 216 supporting a thicker portion 222 having a right angle edge 172, whose irregularities really constitute the effective working record, as will more fully appear from said original application.

In the use of this invention, it is supposed that the operator is equipped with the long strip of record 222—216 from which it is desired to produce audible sounds, as with any phonograph, and for this purpose, this record is run through a reproducing machine of the type shown in Figures 1 and 5, inclusive. A preferred form of the device is shown conventionally mounted inside of a case 228 provided with record carrying reels 230 and 232 between which the record may be passed over driving rollers 234 suitably power actuated and an intermediate roller 236. At one side of the case there is a large opening 238 over which fits the resonator 114, provided with an ordinary reproducing disc 240 of metal, mica or any other commercial form of material. This resonator carries a frame 244 carrying soft rubber pivot bearings 242 between which is journaled a shaft 246 of a reproducing rod 248 adapted to contact the line 172 of the record 222 at an angle thereto as shown in detail in Figure 4 and be held in contact therewith by a spring 250 as shown in Figure 2. The soft rubber bearings 242 are important in absorbing undue vibrations which might affect the reproducer. This rod 248 extends transversely of the record 222—216 and completely across it and the record is located near the end of the rod so that there is ample opportunity for the rod to follow all of the small movements and variations of the curved line 172 as the record passes under the rod thereby insuring transmission of those variations from the rod 248 through a connecting rod 252 attached

to the diaphragm 240 with the result that all the variations in the record 222 are transmitted to the diaphragm and consequently into the air as sound, such sound being, because of the accuracy of the machine and the methods followed an exact reproduction of the sounds initially delivered into the resonator of the receiving machine.

Particular attention is called to Figure 4 10 which shows exactly how the rod 248 travels only on the edge 172 of record 222 as distinguished from contacting the upper surface of the thickened portion 222 and thereby insuring that the record undulations of 15 line 172 are all accurately transmitted to the reproducer.

It is, of course, to be understood that the markings of line 172 in the various drawings are very much exaggerated for purposes of illustration but records made by 20 this method do in fact vary in the same way that they are illustrated and the machine does produce in actual practice the sounds recorded.

25 Figure 5 shows a modified form of construction in which the reproducing bar 248 instead of operating directly upon the diaphragm 240, operates in conjunction with a transmitting magnet 254 connected in 30 circuit through the wires and electrical mechanism 256 with a reproducer magnet 258 adapted to operate the diaphragm 240^a of a distant resonator 114^a. Under this construction the members 240^a and 248 may 35 be miles apart without affecting the result. This feature is reserved for divisional application, Serial No. 593,193.

Having thus fully described my invention, what I claim as new and desire to secure by Letters Patent, is:

1. In mechanism of the class described, in combination with a wheel carrying on its surface a record strip carrying a record having a top surface parallel to the 45 flat surface of the strip and record indentations in its side, a reproducing bar pivotally mounted at one side of the wheel and extending onto said strip in contact with the outer corner of the raised portion 50 of the record where the indentations are and at an angle to the upper surface of the record and a reproducing diaphragm con-

nected to said lever whereby the variations in the record are reproduced on the diaphragm.

2. In combination with a normally flat movable record having record indentations of substantial depth perpendicular to the face of the record, a reproducing bar pivotally mounted in the plane of and at a 60 distance from the record and contacting the corners of the indentations in the record at an angle to the normal flat surface of the record.

3. In mechanism of the class described, 65 in combination with a wheel carrying on its circumference, parallel to its axis, a carrier formed with a flat surface, having thereon a raised portion, said raised portion having sound record indentations in one edge and 70 extending in varying widths cross-wise of the carrier, the portion being of sufficient height above the strip to mechanically affect the transmitting device engaging said indentations; a reproducing bar, pivotally 75 mounted at one side of the wheel and extending onto said carrier, in contact with said indentations, at an angle to the upper surface of the carrier; and a reproducing diaphragm connected to said lever whereby 80 the variations in the record are reproduced on the diaphragm.

4. In mechanism of the class described, 85 in combination with a wheel carrying on its circumference, parallel to its axis, a carrier formed with a flat surface, having thereon a raised portion, said raised portion having sound record indentations in one edge at 90 right angles to the surface of the carrier and extending in varying widths cross-wise of the carrier, the portion being of sufficient height above the strip to mechanically affect the transmitting device engaging said indentations; a reproducing bar, pivotally 95 mounted at one side of the wheel and extending onto the carrier, in contact with said indentations, at an angle to the upper surface of the carrier, and a reproducing diaphragm connected to said lever whereby 100 the variations in the record are reproduced on the diaphragm.

In witness whereof, I have hereunto subscribed my name.

HOWARD L. PAGE,
